UNITED STATES PATENT OFFICE.

HEINRICH LOHMAN, OF AIX-LA-CHAPELLE, GERMANY.

BEVEL-POLISHING MACHINE.

No. 868,877.

Specification of Letters Patent.

Patented Oct. 22, 1907.

Application filed July 25, 1906. Serial No. 327,763.

To all whom it may concern:

Be it known that I, HEINRICH LOHMAN, a subject of the King of Prussia, residing at Aix-la-Chapelle, No. 109 Lütticherstrasse, in the Kingdom of Prussia, Empire of Germany, have invented certain new and useful Improvements in Bevel-Polishing Machines; and I do hereby declare the following to be a full, clear, and exact description of the invention, such as will enable others skilled in the art to which it appertains to make 10 and use the same.

My present invention relates to a machine for polishing bevels and more particularly bevels of plate-glass, in which the polishing-tools execute one oscillating movement during the same time they execute a series 15 of linear motions, whereby not only considerable time is saved but also the deeper lying cavities in the bevels are provided with just as high a degree of polish as usually only the higher lying parts of the bevels receive, because such cavities cannot be reached by the 20 head of a polishing-tool which simply moves back and forth on a straight line.

In the accompanying drawing:—Figure 1 is a side elevation of the new bevel-polishing machine. Fig. 2 is a plan view of said bevel-polishing machine with 25 certain parts shown in section. Fig. 3 is an end view of the machine with parts shown in section with the driving means.

On the table 1 a slide-way 2 is arranged for the slide 3, which is guided by the rib 4 and carries the polishing-tools 5. Each polishing-tool consists of a felt-faced polishing-head 32 and of a vertical spindle 10 to which the polishing-head is hinged in a manner that the latter can adapt itself freely to any bevel to be polished. The polishing-head is pressed against the bevel by a weight 35 carried by said spindle, but can be raised and retained in its elevated position by a hand-operated stop-lever 33 as will be more fully explained later on. The slide 3 receives its motion from the eccentric 6 seated on the driving shaft 7, which may be either a motor-shaft, as indicated, or a line-shaft, as circumstances 40 may direct. The transmission of the motion of the eccentric 6 to the slide 3 is accomplished by means of the eccentric-rod 8. In the known bevel-polishing machines the polishing-tools 5 are simply moved back and forth on a straight line, which arrangement shows this 45 drawback that at places where cavities are ground into the bevels of the glass-plate 9 such bevels cannot be faultlessly polished. This drawback is avoided by the present bevel-polishing machine by letting the polishing-tools accomplish a slow oscillating movement during the time they execute a series of linear motions, which is accomplished in the following manner:—To 50 the spindle 10 of each polishing-tool 5 an arm 11 is attached in any suitable manner or made to form an integral part thereof, and the free ends of these arms are held in recesses 12 of the bar 13 which is guided in the

forked ends of the posts 14 secured to the slide 3. With one end of this bar is connected the one arm of the bell-crank 15 fulcrumed in the bracket 16 likewise secured to the slide 3. The other arm of the bell-crank 15 is connected with a rod 17 which swings on a pin 18 of the lever 19 fulcrumed to the over-head bracket 20. To the pin 21 arranged on the other side of the lever 19 the rod 22 is pivoted and connected at its lower end with the horizontal arm of the bell-crank 23 pivoted to the bracket 24 arranged sidewise of the slide 3 on the table 1. The second arm of the bell-crank 23 is attached to the turned-up arm of the double-armed lever 25 pivoted on the pin 26 likewise secured to the table 1. The longer arm of this 70 double-armed lever is attached to the connecting-rod 27 by means of the link 28, which rod receives its motion from the crank-pin 29 of the wheel 30 driven by the pinion 31 of the motor shaft 7.

It is evident that the ratio the slow oscillating movement of the polishing-tools bears to the number of times the linear motions of the polishing-tools are executed during the same unit of time wholly depends on the ratio the pinion 31 bears to the wheel 30, and that the angle α described by the oscillating heads 32 80 of the polishing-tools 5 is given by the linear motion of the bar 13. This arrangement of parts offers, besides the advantages enumerated above, this advantage that the polishing material can be retained between the heads 32 and the bevel without difficulty. 85

The operation of the machine is as follows:—At each revolution of the driving-shaft 7 the slide 3 will be moved once back and forth, during which motion the rod 17 linked to the bell-crank 15 will swing once to and fro, but as the bar 13 takes part on this motion of 90 the slide 3 it cannot oscillate the polishing-tools 5. Besides this oscillating motion of the rod 17, caused by the motions of the slide 3, it is compelled to execute simultaneously therewith an up and down movement through the instrumentality of the parts 19, 22, 23, 25 95 and 27 operated by the wheel 30 and pinion 31. This up and down movement of the rod 17 depends on ratio the wheel and pinion bear one to another and will take place only once during the same time a series of revolutions of the shaft 7 or the same series of back and forth motions of the slide 3 is executed. The up and down movements of the rod 17 cause the swinging motions of the bell-crank 15 and therefore the linear motion of the bar 13, whereby the polishing-tools 5 are slowly oscillated because said bar operates the arms 100 11. As during these combined motions of the polishing-tools the latter always shift their position on the bevel, and the heads 32 are hinged to the weighted spindles 10 of the polishing-tools in such a manner that they can easily accommodate themselves to the bevel, 105 a polished bevel is obtained which shows at every point such a degree of high polish as hitherto was 110

only obtainable by the far more expensive skilled hand labor. After the bevel has been polished the longer arms of levers 33 fulcrumed adjacent of the spindles 10 are on top of the tubular guides of the brackets 34 are 5 pushed down in order to lift the weights 35, which carry the spindles 10, and the heads 32 of the polishing-tools 5 off the polished bevel. The glass-plate can now be drawn back and shifted to bring another of its bevels beneath the polishing heads 32, or it may be 10 replaced by a new one altogether, as the case may be. After a new bevel has been placed beneath said polishing-heads the levers 33 are manipulated again, but in a reverse way than formerly, to bring said polishing-heads in contact with said bevel, whereupon the polishing operation is commenced anew. 15

I claim:—

1. A bevel-polishing machine comprising polishing-tools capable of executing reciprocating and oscillating motions simultaneously in a true plane, means for causing the reciprocating motions of said polishing-tools, and means for oscillating said polishing-tools around their respective centers independent of the means causing said reciprocating motions of said polishing-tools. 20

2. A bevel-polishing machine comprising polishing-tools capable of executing linear and oscillating motions simultaneously, a slide supporting said polishing-tools, means for moving said slide back and forth, arms carried by said polishing-tools, a bar slidingly arranged upon said slide and straddling said arms, and means for moving said bar independent of the slide carrying it. 25

3. In a bevel-polishing machine of the kind described the combination with a table of a slide-way, a slide arranged on said slide-way, means for imparting linear motion to said slide, brackets on said slide, polishing-tools carried by said brackets, means on said brackets for lifting said polishing-tools off the work-piece, arms on said polishing-tools, forked posts on said slide, a bar slidingly held in the forked ends of said posts and straddling the free ends of said arms, and means for imparting a linear motion to said bar independent of the linear motion of the slide carrying it to oscillate said polishing tools once during the same unit of time they are executing a series of linear motions. 30

In testimony whereof I have signed my name to this specification in the presence of two subscribing witnesses: 45
